UNITED STATES PATENT OFFICE.

DOMINGO NEGROTTI, JR., AND WILLIAM B. FLEMING, OF NEW ORLEANS,
LOUISIANA.

CAR-STARTER.

SPECIFICATION forming part of Letters Patent No. 258,941, dated June 6, 1882.

Application filed March 21, 1882. (No model.)

To all whom it may concern:

Be it known that we, DOMINGO NEGROTTI, Jr., and WILLIAM B. FLEMING, residents of the city of New Orleans, parish of Orleans, and 5 State of Louisiana, have invented a certain new and useful Improvement in Car-Starters; and we do hereby declare the following to be a full, clear, and correct description of the same, reference being had to the annexed drawings, 10 making a part of this specification.

This invention relates to a device in which the power of the draft-animal is applied to give a direct impulse upon the wheels, so as to start or keep the latter rolling.

15 On the drawings, Figures 1 and 2 are longitudinal sections of a car provided with our improvement. Fig. 3 is a transverse section thereof, and Fig. 4 a view of the forward portion of the arrangement. Figs. 5 and 6 are 20 enlarged views of certain parts of same.

The letter A represents the body of a car, B B' the axles, and C C' the wheels thereof.

Our device may be connected with one or 25 more axles; and it consists of a ratchet-wheel, D, having side bosses or projections upon which are loosely fitted a pair of levers, e e', these connected by means of bolts f, having shoulders f', to prevent the levers from pressing against the sides of the ratchet-wheel. Between the aforesaid levers is suspended, on a 30 pin, g, a pawl, H, the free end of which engages the ratchet-wheel whenever it is required to move the same. The pawl is automatically raised by a pin, i, (see Fig. 2,) which projects from the pin g toward the center of the axle, 35 passing between guides k, formed on one side of the levers, and having its end resting in a slot, x, formed in the edge of an annular ring or slide, l, that is fitted so as to turn on the sleeve of a lever, M. The end of the latter rests in a socket, n, whereby it is held in a given position. The ring or slide l may be made of steel, and to prevent its turning too freely on its bearing a portion may be cut out, 40 as in cylinder and pump packing-rings, and shown in dotted lines at x', Fig. 6. A certain amount of play is left in the guide k and slot x, in order that the levers e e' may have a limited movement before imparting the same to 45 the slide l. The latter is dragged, as it were,

by the pin i, which keeps the end of the pawl in contact with the ratchet-wheel until the car is fairly started, which action throws the pawl out of gear, and at the same time moves the slide forward until the end of its slot comes in contact with the rear of the pin i. Thus it is held until the strain upon the levers e is relinquished, when the weight o, through its connecting-rope p p', will draw the latter backward, which movement will reverse the bearings on the pin i, turn the annular ring backward, and throw the pawl into gear again. 55 60

The remaining part of our arrangement consists of a draw-head, R, which is secured by a king-bolt, s, to the forward part of the car. 65 The front portion of this draw-head is provided with two straps, t t', in which bearings are formed for a single-tree, the latter consisting of a round rod, U, which from its bearings is tapered and curved, as shown in Fig. 4. The 70 outer ends of the aforesaid rod are provided with eyes v v' for the reception of the trace-chains. At the center of the rod U, and between the bearings thereof, is a pin or stud, w, which operates in a recess made in the upper 75 rear portion of a short lever, y, the outer end of which is connected by the rope or chain p p' with the levers e e', as shown. The lever y being loosely fitted to the rod U, permits the 80 ends of the same to swing back under the car in the event of their coming in contact with any obstruction.

From the above description it will be seen that the car is moved forward by the pull upon the traces, causing the rod U to turn in its 85 bearings, and through its stud to force the small lever y forward, the said movement being communicated through the rope p, levers e e', and pawl H to the ratchet-wheel D; and also that the pawl is thrown in and out of gear 90 through the weight o, rope p', pin i, and ring or slide l. The rope p p' is of sufficient length to be wound one or more times around the circle formed by the connecting-bolts f of the levers e e', so as to provide for the pawl traveling the whole or any part of the circle. 95

Having described our invention, what we claim as new, and desire to secure by Letters Patent, is—

1. In a car-starter, a ratchet-wheel, D, hav-

ing side bosses on which are fitted levers $e e'$, connected by means of bolts f , around which the rope $p p'$ is wound, as described, and for the purpose set forth.

- 5 2. In a car-starter, the annular ring or slide l , fitted on a stationary bearing, and provided with a slot, x , in which operates the end of a pin, i , said pin being connected with the pawl H , and acting in guides k of the lever e' to throw the pawl in or out of gear, as described, and for the purpose set forth.
- 10 3. In combination with a car-starter composed of a ratchet-wheel, D , operating-levers

$e e'$, and pawl H , a draw-head, R , provided with straps $t t'$, forming bearings for a single-tree, U , having a stud, w , for operating a lever, y , connected with the starter, as described, and for the purpose set forth. 15

In testimony whereof we have hereunto signed our names,

DOMINGO NEGROTTI, JR.
WILLIAM BURNSIDE FLEMING.

In presence of—

J. C. HUBBELL,
P. J. FINNEY.
